UNITED STATES PATENT OFFICE.

EDWARD ALFRED GRAHAM, OF LONDON, ENGLAND; MARIA GRAHAM AND ALFRED GRAHAM EXECUTORS OF SAID EDWARD ALFRED GRAHAM, DECEASED.

COMBINED GRAMOPHONIC AND TELEPHONIC SOUND DUCT.

Application filed March 20, 1925, Serial No. 17,109, and in Great Britain April 3, 1924.

In the specification of my application Serial No. 713,234, filed 14 May, 1924, there is described an invention which consists in introducing the sound duct associated with a wireless telephone receiver into the sound duct associated with a gramophone or the like in suchwise as to enable a single horn or acoustic amplifier common to the two sound reproducers to be effectively employed.

10 Included in the examples chosen for illustration is a gramophone tone arm supported by a stationary mounting of any ordinary or commercial type, except that it is provided with the duct of a telephonic receiver to be introduced into the sound duct of the gramophone.

The object of the present invention is to effect further improvements and it consists in utilizing an internal stationary or fixed 20 portion of the mounting of a gramophone tone arm, which portion constitutes part of the introduced sound duct of any telephonic receiver, as a means for carrying, in whole or in part, the said gramophone tone arm.

25 To this end, the portion of the telephonic duct introduced into the gramophone duct is adapted to co-operate with the tone arm, or a fitting or fittings thereof.

In the accompanying drawings, whereof Fig. 1 is a perspective view illustrating the general appearance of a combined gramophone tone arm, a mounting therefor and telephonic receiver, Figs. 2, 3, 4 and 5 are vertical sections depicting four different 30 constructional arrangements according to the invention. Fig. 6 is an elevation at right angles to Fig. 4. Fig. 7 is a sectional detail view showing a further modification.

As shown in Fig. 2, the mounting *a*, 40 which is fixed to that portion *b* of a gramophone, known as the motor-board, and is formed interiorly with the member *c* constituting the emission extremity of a sound duct from a telephonic receiver, such as *d* (Fig. 1), is, in addition, formed with a boss *e* bored to constitute a plain bearing for a pivot pin *f*, carried by a spider *g*¹ in the tone arm *g*, and for a retaining screw *h*.

The tone arm is thus supported entirely by 50 the bearing at *e*, as it also is in the case of Fig. 3, which differs only from Fig. 2 in that races are provided to receive balls *i* between a collar *j* on the pin *f* and the boss *e* and also

balls *k* between the latter and the head of the retaining screw *h*. 55

In Fig. 4, the tone arm is supported in part by the bearing at *e*, having a single race of balls *k*, and in part by a race of balls *i* interposed between the tone arm proper and the mounting *a*. 60

Fig. 5 illustrates a modification in which the member *c* is provided with a bearing arrangement the same as that shown in Fig. 2, the tone arm *g*, however, being of a type that is movable about the horizontal axis of a pin *m* in relation to the pivot pin *f*. A spring *n*, coiled around the pin *m*, is shown as provided to take parts of the weight of the tone arm so that undue pressure shall not be exercised by the stylus on the disc record in cases where, unlike that of Fig. 1 in which a goose neck *o* is employed, the gramophone reproducer or sound box is rigidly attached to the outer extremity of the tone arm. 75

Figs. 4 and 6 further illustrate the tone arm as equipped with a valve *p* by means of which the volume of sound from the gramophone reproducer or sound box can be regulated, or by which the acoustic passages in 80 the tone arm can be entirely closed when desired, the aperture being varied or closed by manipulating the valve, as through the linkage *r*, spindle *s* and exterior knob *t*.

To those versed in the art of telepathy 85 and with knowledge of gramophone design and construction, it will be obvious that the present invention can be carried out in divers manners without departing from the essential feature or spirit of the invention which provides a gramophone tone arm or acoustic conduit into which is introduced a duct from a telephonic receiver in an advantageous manner, considered acoustically, at the same time providing an improved and useful mechanical means for mounting or carrying the movable portion of the combined arrangement. 90

Thus, the upper part of the bearing portion *e* of the duct *c*, may as shown at *e*¹ in 100 Fig. 7, be adapted to act as a fixed spindle, journal, arbor or the like to co-operate with a bearing *g*² formed in or carried by the movable tone arm, as for instance by the central portion or boss *g*² of the spider *g*¹, the pin *f*¹ that fixed the said boss to the pin *f* in 105

Fig. 2, being then removed. Or the pin f^1 of Fig. 2, may be fixed to the bearing portion e of the sound duct c , as by tightening up the screw h sufficiently to cause it and a collar f^2 on the pin to clamp the bearing portion e between them, so that by removing the aforesaid pin f^1 , the said pin f will serve as a fixed spindle, journal, or arbor for the bearing portion g^2 of the spindle g^1 and tone arm.

What I claim is:—

1. Combined gramophonic and telephonic sound ducts of the kind herein referred to, comprising a gramophone sound duct having stationary and movable portions and a telephonic sound duct extending into the stationary portion of said gramophonic sound duct and upon which the movable portion of said duct bears.

2. Combined gramophonic and telephonic sound ducts of the kind herein referred to, comprising a gramophonic sound duct having stationary and movable portions and a telephonic sound duct extending into the stationary portion of said gramophonic sound duct and forming a bearing that wholly supports the movable portion of the gramophonic sound duct.

3. Combined gramophonic and telephonic sound ducts, of kind herein referred to, comprising stationary and movable portions of a gramophonic sound duct, a telephonic sound duct extending into the stationary portion of the gramophonic sound duct, a bearing formed by a portion of the wall of said telephonic sound duct within the stationary portion of the gramophonic sound duct, a second bearing carried by the movable portion of said gramophonic sound duct and pivotal connecting means carried by the first mentioned bearing and cooperating with said second mentioned bearing.

4. In combined gramophonic and telephonic sound ducts of the kind herein referred to, a gramophonic sound conduit comprising a movable tone arm and a stationary mounting therefor, a telephonic sound conduit a portion of which extends into said mounting and a pivotal connection between the portion of the telephonic sound duct within said mounting and the adjacent end of the tone arm.

5. In combined gramophonic and telephonic sound ducts of the kind herein referred to, a gramophonic sound conduit comprising a movable tone arm and a stationary mounting therefor, a telephonic sound conduit a portion of which extends into said mounting, and a vertical pivot carried by the portion of the telephonic sound duct within said mounting and coacting with the adjacent end of the tone arm and about the axis of which said tone arm can turn.

6. In combined gramophonic and telephonic sound ducts of the kind herein re-

ferred to, a gramophonic sound conduit comprising a movable tone arm and a stationary mounting therefor, a telephonic sound conduit, a portion of which extends into said mounting and is adapted to form a bearing, and a pivotal connection attached to the adjacent end of said tone arm and mounted to turn in said bearing.

7. In combined gramophonic and telephonic sound ducts of the kind herein referred to, a gramophonic sound conduit comprising a movable tone arm and a stationary mounting therefor, a telephonic sound conduit a portion of which extends into said mounting and is adapted to form a bearing, a pivotal connection mounted to turn in said bearing, about a vertical axis, a horizontal pin carried by said pivotal connection and on which the adjacent end of the tone arm is mounted to turn in a vertical plane and a spring carried by said pivotal connection and adapted to take part of the weight of the tone arm.

8. Combined gramophonic and telephonic sound ducts comprising stationary and movable portions of a gramophonic sound duct and a telephonic sound duct extending into the stationary portion of the gramophone sound duct and means for regulating the volume of sound emitted from said gramophonic sound duct.

9. Combined gramophonic and telephonic sound ducts comprising stationary and movable portions of a gramophonic sound duct, a telephonic sound duct extending into the stationary portion of the gramophonic sound duct and hand operated means for regulating the volume of sound emitted from said gramophonic sound duct.

10. Combined gramophonic and telephonic sound ducts comprising stationary and movable portions of a gramophonic sound duct, a telephonic sound duct extending into the stationary portion of the gramophonic sound duct, a valve located within the movable portion of said gramophonic sound duct and hand operated means for regulating the position of said valve and the volume of sound emitted from said gramophonic sound duct.

11. In combined gramophonic and telephonic sound ducts of the kind herein referred to, a gramophonic sound conduit comprising a movable tone arm and a stationary mounting therefor, a telephonic sound duct a portion of which extends into said mounting; a pivotal connection between the portion of the telephonic sound duct within said mounting and the adjacent end of said tone arm, and means for regulating the volume of sound passing through said gramophonic sound duct.

12. In combined gramophonic and telephonic sound ducts of the kind herein referred to, a gramophonic sound conduit comprising a movable tone arm and a stationary

mounting therefor, a telephonic sound conduit a portion of which extends into said mounting, a pivotal connection between the portion of the telephonic sound duct within said mounting and the adjacent end of said tone arm, a flap valve for regulating the volume of sound passing through said gramo-

phonic sound duct and hand operated mechanism for manipulating said valve to close said valve or to open it to varying extents. 10

Signed at London, England, this ninth day of March, 1925.

EDWARD ALFRED GRAHAM.
